Filed Nov. 15, 1972, Ser. No. 306,568

Term of patent 14 years

Int. Cl. D30—03

U.S. Cl. D30—13

FIG. 1 is a front, top and left side perspective view of a holder for a food bowl for pets or similar article showing my new design with the turn lock in closed position;

FIG. 2 is a right side view with the turn lock in closed position;

FIG. 3 is a top view with turn lock in open position;

FIG. 4 is a back view with turn lock in closed position; and

FIG. 5 is a right side view similar to that of FIG. 2 with the turn lock in open position.

A portion of FIG. 1 has been shaded to indicate contrast in appearance.

I claim:

The ornamental design for a holder for a food bowl for pets or similar article, as shown and described.
